UNITED STATES PATENT OFFICE.

DANIEL E. REAGAN, OF COLUMBUS, OHIO.

BRICKMAKING-MACHINE.

1,226,115.

Specification of Letters Patent.

Patented May 15, 1917.

Application filed March 18, 1916. Serial No. 85,091.

To all whom it may concern:

Be it known that I, DANIEL E. REAGAN, a citizen of the United States, and a resident of Columbus, in the county of Franklin 5 and State of Ohio, have invented certain new and useful Improvements in Brickmaking-Machines; and I do hereby declare the following to be a full, clear, and exact description of the invention, such as will enable others skilled in the art to which it 10 appertains to make and use the same.

My invention relates to an improvement in brick making machines, and particularly to machines for the manufacture of paving 15 bricks having projections on one or more faces for holding them apart so as to permit the cement, grout or other filler commonly used for binding purposes, to be readily poured or inserted between the bricks or 20 blocks, and which also facilitate the laying of said bricks by keeping them in alinement.

The object of the invention is to provide 25 an attachment which may be applied to the ordinary brick making machine for finishing the two faces of the clay bar as it leaves the machine and for forming the projection on one face.

A further object is to provide means whereby the weight and friction of the moving bar of clay actuates the finishing rolls 30 of my attachment.

With these ends in view my invention consists in the parts and combination of parts 35 as will be more fully explained and pointed out in the claims.

In the accompanying drawings, Figure 1 is a view in front elevation of my improvement; Fig. 2 is a view in side elevation of the same; Fig. 3 is a view in plan the oil 40 cups being omitted; Fig. 4 is a view in longitudinal vertical section through Fig. 2; Fig. 5 is a detached view of the shaft carrying the upper roll as shown in full lines in Fig. 1; Fig. 6 is a view in perspective of 45 one of the bricks; Fig. 7 is a view showing two bricks in their assembled position; Fig. 8 is a view in perspective of the liner; Fig. 9 is a view in section similar to Fig. 4 showing a clay bar passing through the machine 50 and a marker for the bar, and Fig. 10 is a view of the upper roller constructed as illustrated in dotted lines in Fig. 1.

1 represents a die plate provided at suitable points with bolt holes for the passage of 55 the bolts which secure the plate to the head

of a brick making machine. This plate 1 is provided with an opening conforming in size and shape to the opening in the head of the brick machine, and is also provided with the forwardly or outwardly projecting 60 integral side frames 2 and upper and lower projecting flanges 3 and 4. The sides 2 and flanges 3 and 4 are located at the four sides of the opening in the plate 1, and support the lining 5 which is in effect a die. 65 The upper member of this lining is slightly inclined downwardly toward its outer end as shown in Fig. 9, so that the clay bar will be compressed and slightly reduced in depth as it passes through the die. The liner may 70 have slots as shown in the upper side where it comes in contact with roll 6, to permit of greater expansion of clay in the recesses or pockets in roll 6, for the formation of projections, and it may have ridges on top and 75 bottom members, to assist rolls in producing longitudinal grooves in top and bottom of clay bar, which are finished by corresponding ridges in top and bottom roll. The said 80 ridges produce grooves or troughs on the two sides of brick, so that when bricks are laid together they form a recess for holding the grout, producing an interlocking bond 85 which securely holds the paving brick in position.

Located at the outer edge of the top member of the lining is the roll 6, the said lining being cut away and grooved as shown so as to permit the roll to lie close to the same and in a position to engage the clay bar as 90 it leaves the top member of the lining, without any space between them into which the clay could pack, the said roll forming in effect a part of the die, as it imparts the finish to the upper face of the clay bar. 95

This roll 6 is provided with a central enlargement 7 for forming a central groove 8 longitudinally of the upper face of the brick 9, and is also provided at each side of said enlargement with one or more recesses or 100 pockets 10 into which the clay of the bar enters to form corresponding projections 11 on the upper face of the brick. This roll may extend slightly beyond the side of the die opening as shown at dotted lines 12 in 105 Figs. 1 and 10, or of less width as in Fig. 5 and in full lines Fig. 1, with its ends in close relation to the shoulders 13 formed on the upper member of the lining 5. With either of these constructions I am enabled to pro- 110

vide for slightly rounded corners as at 14, thus producing similarly rounded corners on the brick.

The roll 6 may be integral with or secured 5 to the shaft 15 by keys or otherwise, and is mounted in anti-friction bearings carried by the blocks 16. The blocks 16 are mounted at the upper ends of the side members 2, as shown in Fig. 2, and are secured thereto 10 by the bolts 18, which are screwed into threaded openings formed in the upper ends of the side members 2. Each bolt 18 has a shoulder 19 thereon at the upper end of the threaded portion, which shoulders rest in 15 pockets formed in the lower edges of the blocks 16, hence by turning the bolt, the blocks carrying the roll 6 can be adjusted vertically so as to accurately locate and adjust the roll 6 with relation to the front end 20 of the die. These bolts 18 pass upwardly through the blocks 16 and secure them to the side frames and in proper relative position.

Mounted in ball bearings at the lower ends 25 of the sides 2 and secured therein by the half bearings 19^a, is the shaft 20 carrying the lower roll 21, which as shown in Fig. 1 is preferably as long as the die is wide so as to completely support the clay block as 30 it emerges from the die. The roll 21 rests in a plane slightly in advance of the roll 6 as clearly shown in Fig. 2, and beyond the outer end of the lining 5, of the die, so that the clay bar, as it emerges from the die will 35 be wholly supported by said lower roll and rotate it in the direction of movement of the clay bar.

This roll 21 is provided with a central enlargement 22 for engaging and finishing the 40 groove 23 on the lower face of the brick 9, which enlargement may have thereon marks, such as the trade-mark, or name of the brick, the name of the maker, etc., which marks or letters either sunken or raised, will 45 of course assist the weight of the clay bar in turning the roll 21.

Secured to shaft 20 is the pinion 23 which meshes with a smaller pinion 24 secured to shaft 15 carrying roll 6, so that the rotation 50 of the roll 21 will rotate the roll 6. From this it will be seen that the outward movement of the clay bar rotates the rolls. Hence the movement of the latter always conforms to the speed of movement of the 55 bar as it emerges from the machine.

Secured to the tops of the blocks 16, and in front of the roll 6, is the plate 24^a, recessed on its top to receive the wiper holder 25. This holder is recessed on its under face 60 to receive the felt or other wiper 26 the free edge of which bears against the periphery of the roll 6 and operates to keep the latter free of any adhering particles of clay. This wiper may carry oil or other lubricant for lubricating the roll so as to lessen the tend-

ency of the clay to adhere thereto. The holder 25 is provided at its ends with elongated slots for the screws 27 which secure it to the plate 24^a, and it is forced toward the roll by the screws 28 carried by the plate 24^a and bearing at their inner ends against the front edge of holder 25.

In order to prevent the condensed steam or water used for lubricating from dripping onto the lower roll, I employ the drain 28 in the bottom of the extension, so located as to discharge the dripping in a plane to the rear of the lower roll. This is an important factor in preventing slippage of the clay column on the bottom roll.

This improvement is designed to be attached to any stiff mud brick machine, and the rolls thereof are positively actuated by the passage of the clay or mud bar through the die. The rolls are not pressure rolls in 85 the sense that they or either is forced by spring or otherwise against the clay bar, nor is the upper roll so located that it acts on a surface of the bar fully shaped by the die, but on the contrary it is so located with 90 relation to the die, and at a point where the clay being forced through, is under pressure so that the recesses in said upper roll will be filled by the pressure forcing the clay outwardly and not wholly by the expansion 95 of the clay after it has been shaped.

The lugs or projections 11 on the bricks are preferably curved as shown and are so located that each brick or block formed will have a plurality of projections on one side, 100 which as before explained operate to hold the bricks or blocks sufficient distance apart while being laid to permit cement, grout or other filler to be readily poured or inserted between the bricks, and to keep them 105 in alinement.

In Fig. 9 I have shown a frame 29 secured to the plate 24^a by the screws 18 and carrying a roller 30 which turns freely on the axle 31 secured to the frame 29, the said 110 roller having raised letters thereon for impressing a word or name in the upper groove 32 of the clay bar.

It is evident that many slight changes might be resorted to in the relative arrangement of parts shown and described without departing from the spirit and scope of my invention. Hence I would have it understood that I do not wish to confine myself to the exact construction shown and described, but

Having fully described my invention what I claim as new and desire to secure by Letters-Patent, is:-

1. In an attachment for a brick machine, 125 the combination of a frame having a die opening and flanges at the four sides thereof, a removable four sided integral die or lining within said opening and supported by the flanges, the top member of said die being 130

cut away at its outer end, the cut away edge being shaped to conform to the periphery of a roll, a roll carried by the frame and located adjacent the free edge of the bottom 5 of the die and in a position to receive the clay bar and be rotated thereby, and a roll mounted in said frame adjacent the free edge of the top of the die with its lower portion resting in the said cut away and 10 recessed portion of the die, whereby the lower portion of the roll forms a continuation of the upper side of the die.

2. In an attachment for brick making machines, the combination of a frame having a 15 box like opening, a removable four sided integral die or lining for said opening, the top member of said die being cut away and recessed at its outer edge and provided with a longitudinal ridge on its lower face, a roll carried by the frame and located adjacent the free edge of the bottom of the die in a position to receive the clay bar and be rotated thereby, the said roll being provided with a peripheral enlargement 20 conforming to the ridge on the die, a roll adjustably mounted in the cut away and recessed portion of the die, and gearing connecting the two rolls whereby they will be rotated in unison by the movement of the 25 clay bar as it is ejected from the machine.

3. In an attachment for brick making machines, the combination of a die, a positively driven roll located to engage the top face of the clay bar as it is forced from the machine, a holder movably mounted with relation to said roll, means for moving and for 30

35

locking said holder in place, and a wiper carried by the holder and engaging the periphery of said roller.

4. In an attachment for brick making machines, the combination of a die, a positively driven roll located to engage the top face of the clay bar as it is forced from the machine, the said roll having a plurality of recesses or pockets in its periphery and a peripheral enlargement, a flexible wiper and lubricator engaging the periphery of said roll, a holder for said wiper, and means for moving the holder toward the roll and adjustably secured to said frame. 40

5. In an attachment for brick making machines, the combination of a die, a roll located to receive the weight of the clay bar as the latter is forced from the die, a roll located to engage the top face of the clay 45 bar and mounted in bearings which are adjustable toward and from the clay bar, the said latter roll having a plurality of recesses or pockets in its periphery, gearing connecting said rolls whereby they will be positively 50 rotated by the movement of the clay bar, and an adjustable holder carrying a flexible wiper engaging the periphery of the top roll. 55

In testimony whereof, I have signed this 60 specification in the presence of two subscribing witnesses.

DANIEL E. REAGAN.
